Primary Examiner—Doris Clark*Assistant Examiner*—Anhdao Doan(74) *Attorney, Agent, or Firm*—Knobbe Martens Olson & Bear LLP(57) **CLAIM**

I claim the ornamental design for a support pole for a sheltering structure, as shown and described.

DESCRIPTION

FIG. 1 is a fragmentary view of a support pole for a sheltering structure showing the new design;

FIG. 2 is a top plan view of the design of FIG. 1;

FIG. 3 is a bottom plan view of the design of FIG. 1;

FIG. 4 is a fragmentary first side elevation view of the design of FIG. 1;

FIG. 5 is a fragmentary second side elevation view of the design of FIG. 1;

FIG. 6 is a fragmentary third side elevation view of the design of FIG. 1; and,

FIG. 7 is a perspective view of the support pole of FIG. 1 showing an umbrella in phantom lining, an umbrella being one environment in which the new design can be used.

The broken line showing of the umbrella in FIG. 7 and the broken lines in FIGS. 1-3 showing internal structures of the support pole design are for illustrative purposes only and form no part of the claimed design.

The support pole for a sheltering structure is shown broken away to indicated indeterminate length.
